OTHER PUBLICATIONS

U.S. Appl. No. 61/916,593, filed Dec. 16, 2013, titled "Container for Disposable Spray Gun Components".

Primary Examiner — Robert M Spear

Assistant Examiner — Marissa J Cash

(74) *Attorney, Agent, or Firm* — Aleksander Medved

(57) **CLAIM**

The ornamental design for a container for disposable spray gun components, as shown and described.

DESCRIPTION

FIG. 1 is a perspective view of a container for disposable spray gun components embodying the new design;

FIG. 2 is a front view of a container for disposable spray gun components embodying the new design;

FIG. 3 is a rear view of a container for disposable spray gun components embodying the new design;

FIG. 4 is a left side view of a container for disposable spray gun components embodying the new design (the ride side view is a mirror image of the left side view and therefore is not shown);

FIG. 5 is a top view of a container for disposable spray gun components embodying the new design; and,

FIG. 6 is a bottom view of a container for disposable spray gun components embodying the new design.

The claim is limited to the opening in the container depicted in solid lines; no portion of the interior or exterior container surfaces form any part of the claim.

1 Claim, 3 Drawing Sheets
